UNITED STATES PATENT OFFICE.

WILLIAM G. L. TOTTEN, OF BUCKHANNON, WEST VIRGINIA.

BRAKE-SHOE.

1,245,824.

Specification of Letters Patent. Patented Nov. 6, 1917.

Application filed October 14, 1916. Serial No. 125,617.

To all whom it may concern:

Be it known that I, WILLIAM G. L. TOTTEN, a citizen of the United States, residing at Buckhannon, in the county of Upshur and State of West Virginia, have invented new and useful Improvements in Brake-Shoes, of which the following is a specification.

This invention relates to brake shoes and 10 it consists in the novel features hereinafter described and claimed.

An object of the invention is to provide a 15 brake shoe of simple and durable structure adapted to be applied to the driving wheels of a locomotive or the wheels of a car truck, the shoe being of such a structure as to frictionally engage the wheels and also to frictionally engage the track rail whereby the 20 wheel is prevented from slipping upon the rail when the brake shoe is applied, thus protecting the tire of the wheel against wear.

With this object in view the invention includes in combination with a block having a groove disposed transversely across its 25 edge a brake shoe of a length sufficient to extend from the said block to the track rail when the brake is applied. The shoe is provided with a rib which fits in the said groove and is provided with a flange at its upper 30 end which engages the upper end of the said block. The shoe is provided at its lower portion and at its opposite sides with lugs adapted to receive the track rail between them whereby the lower portion of the shoe is 35 held in proper position with relation to the rail when the shoe is applied to the periphery of the wheel.

In the accompanying drawing:

Figure 1 is a side elevation of the brake 40 shoe showing the same applied to a block and its relative position with relation to a wheel and track rail.

Fig. 2 is a vertical sectional view through the brake shoe.

Fig. 3 is an under plan view of an end 45 portion of the shoe.

Fig. 4 is a transverse sectional view through the track rail cut on the line 4—4 of Fig. 2.

As illustrated in the accompanying drawing, the block 1 is provided at its rear side with a transversely disposed groove 2, and the said block is attached to a brake link 3 and beam 4 in the usual manner.

The brake shoe 5 is provided at its upper forward portion with a rib 6 which fits

snugly in the groove 2 and the said shoe is provided at its upper end with a flange 7 which engages over the upper end of the block 1. A bolt 8 passes transversely 60 through the shoe and the intermediate portion of the block 1 and serves as a means for holding the said shoe in position upon the block. The shoe 5 is of a length sufficient to extend from the block 1 to the track rail 65 9 when the shoe is applied to the periphery of the wheel 10. The shoe 5 is provided at its lower end and at its opposite edges with lugs 11 which are adapted to receive the head of the track rail between them when 70 the shoe is applied to the periphery of the wheel 10. The lug 11 at the inner side of the track rail 9 is a little shorter than the lug 11 at the outer side thus providing sufficient space or room for receiving the flange 75 of the wheel 10.

When the block 1 is moved so that the shoe 5 is applied to the periphery of the wheel 10, the said shoe frictionally engages the wheel and the lower portion of the shoe 80 extends under the wheel and bears directly against the upper surface of the head of the track rail 9 whereby the said wheel is lifted from the track rail and the shoe is interposed between the wheel and track rail. 85 During this movement of the shoe, the lugs 11 direct the lower portion of the shoe under the wheel and prevent the shoe from moving laterally from between the wheel and track rail. Consequently it will be seen 90 that when the shoe is applied, the wheel is lifted from the rail and the shoe frictionally engages the rail thus relieving the tire of the wheel from wear and preventing the same from becoming flattened as is the case 95 in usual construction when the brake shoe is applied to the wheel with sufficient force to bring the wheel to a state of rest while it slides along the track rail.

Having described the invention what is 100 claimed is:

1. In combination with a block having a transversely disposed groove, a brake shoe having a rib adapted to be received by the groove and provided with a flange adapted 105 to engage over the end of the block, said shoe being of a length sufficient to extend from the block to the track rail when the shoe is applied, the shoe being provided at its lower portion and at its opposite sides 110 with spaced lugs.

2. In combination with a block having a

transversely disposed groove, a brake shoe having a rib adapted to enter the groove and provided with a flange adapted to engage over the end of the block, the shoe being of a length sufficient to extend from the block to the track rail when the shoe is applied, the shoe being provided at its lower

portion and at its opposite sides with lugs adapted to lie at the opposite sides of the head of the track rail, the lug at the inner 10 side of the rail being shorter than the lug at the outer side.

In testimony whereof I affix my signature.
WILLIAM G. L. TOTTEN.
